WEFT DETECTING MECHANISM FOR MULTICOLOR SHUTTLE CHANGERS

Richard G. Turner, Worcester, Mass., assignor to Crompton & Knowles Loom Works, Worcester, Mass., a corporation of Massachusetts

Application April 22, 1933, Serial No. 667,464

26 Claims. (Cl. 139—232)

This invention relates to improvements in weft detecting mechanism for multicolor shuttle changing looms, and it is the general object of the invention to provide a detecting mechanism on the shuttle changing side of the loom which shall enter the active shuttle to effect weft detection.

In multicolor weft replenishing looms there are usually provided shifting shuttle boxes at one side of the loom movable to render active any one of a plurality of weaving shuttles, while the other side of the loom is provided with a shuttle box which during normal operation is common to all the active shuttles. In shuttle changing looms of this general type it has been found desirable to place the weft detecting mechanism at the magazine side of the loom so that it can cooperate with the shuttle box which does not ordinarily move relatively to the lay at the time of detection. Indication storing mechanism can be employed so that a shuttle which indicates exhaustion on any pick of the loom can be changed upon its subsequent arrival under the magazine.

In looms of this type there exists the problem of effecting replenishment without repeating the indication of weft exhaustion. The detector mechanism will detect the shuttles to be replaced upon its subsequent arrival under the magazine unless prevented from doing so. This result may be accomplished by moving the detector away from its normal position when a shuttle is to be changed or the shuttle boxes at the magazine end may be moved in such a way as to prevent a second contact of the detector with the depleted shuttle. This latter result can be accomplished by effecting change of shuttle when the lay is in rear position with the depleted shuttle at its farthest distance from the weft detector.

The invention is particularly adaptable to looms wherein shuttle change is accompanied by movement of a shuttle box toward the supply of reserve shuttles. In such looms the box mechanism must be free to shift at the time of shuttle change without damaging the detector, or having its movements obstructed thereby. This applies both to the rising and falling movements of the shuttle box.

In my co-pending application Serial No. 665,140, I have set forth a loom wherein the detecting mechanism is mounted on a lay carried part and is moved out of the path of the incoming fresh shuttle at the time of shuttle change. In the present instance I employ a detecting mechanism which is mounted on a relatively fixed part of the loom.

In order to prevent the fresh shuttle from breaking the thread of the outgoing shuttle, the latter is preferably discharged forwardly. The most practicable location for the detector is in front of the lay, and it is a further object of my invention to eject the depleted shuttle forwardly without interference with the detector. This result may be accomplished by lowering the empty shuttle to a point below the detector before actual discharge from the lay occurs.

With these and other objects in view which will appear as the description proceeds, my invention relates to the combination and arrangement of parts hereinafter described and set forth in the claims.

In the accompanying drawings, wherein I have shown two forms of detectors,

Fig. 1 is a diagrammatic side elevation of a loom having the preferred form of my invention applied thereto,

Fig. 2 is a side elevation of the lower part of the mechanism shown in Fig. 1 which raises the changing boxes,

Fig. 3 is a top plan view of the selector mechanism looking in the direction of arrow 3, Fig. 2,

Fig. 4 is a detail vertical section on line 4—4, Fig. 3,

Fig. 5 is a side elevation of the upper part of the mechanism shown in Fig. 1,

Fig. 6 shows a detail top plan view of the weft detector shown in Fig. 1,

Fig. 7 is a side elevation, partly in section, of the upper part of a loom having a modified or electrical form of weft detector,

Fig. 8 is a horizontal section on line 8—8 of Fig. 7 through the detector mechanism,

Figs. 9 to 11 are diagrammatic views showing the parts in successive positions at the time of shuttle change, and

Fig. 12 is a fragmentary top plan view looking in the direction of arrow 12, Fig. 10.

Referring particularly to Figs. 1, 2, and 5, I have shown a loom frame 20 on which may be mounted multicolor shuttle changing mechanism of the general form shown in my co-pending application Serial No. 460,746. The magazine M has two different stacks or groups of reserve shuttles, the rear stack being supported by a platform 21 so that the lowest shuttle thereof is directly in front of a plunger 22. The latter may be actuated by a lever 23 rocked to move the plunger forwardly, or to the left as viewed in Fig. 5, whenever the pull rod 24 is lowered. Delivery from the front stack is accomplished by rocking lever 25 by a pull rod 26. A link 27 connects lever 25 with a release arm

28 having a finger 29 which extends under the lowest shuttle of the front stack. When this finger is moved forwardly the bottom shuttle is released, and mechanism not shown herein but set forth in the aforesaid application supports the super-imposed shuttles.

The lay L is provided with rearwardly extending fingers 30 positioned at all times to support a shuttle which is delivered from the magazine. 10 The front shuttles of the magazine fall directly on this plate, while the rear shuttles are pushed thereon from the platform 21. The magazine itself forms no part of my present invention and can deliver shuttles through the throat 31 as 15 disclosed in the aforesaid application and also in copending application Serial No. 560,573.

The mechanism for actuating the pull rods 24 and 26 is shown more particularly in Figs. 2, 3 and 4. A fixed stand 32 mounted on a stationary 20 stud 33 has pivotally mounted at the right hand end thereof as shown in Fig. 2 a positioning lever 34 with a head 35 which has sliding and guiding engagement with the rods 24 and 26. The lower end of each rod has a hook 36, and the position of 25 the hooks horizontally is determined by a flexible connection 37 passing around a sheave 38 and extending to the opposite side of the loom, where it has connection with some part of the shifting box control mechanism, either directly to the 30 boxes or to some part controlled by the pattern chain. These connections may be as shown in the aforesaid application, or as set forth in my co-pending application, Serial No. 665,140.

Shifting of the boxes at the drop box side of 35 the loom is therefore accompanied by a rocking of the lever 34 so that one of the other of said hooks 36 is presented in the path of a lug 39 carried by a normally stationary operating lever 40. The latter is pivoted on the stud 33 and has 40 the forward, or left hand end as viewed in Fig. 2, connected to a box lifter rod 41.

A regularly moving actuator lever 42 is also pivotally mounted on the stud 33 and carries at its forward end a lifting latch 43 pivoted thereto by 45 a pin 44. A coil spring 45 acts to hold the upper end of the latch in the full line position shown in Fig. 4 so that as it rises there will be no contact between the latch and the lug 46 integral with the operating lever 40.

50 The mechanism for controlling the latch is set forth herein in Figs. 2, 3 and 4 and may be substantially the same as shown in co-pending application Serial No. 3,734, filed by Holmes and Cederlund, and is mounted on the operating lever. 55 This mechanism includes a selector frame 50 slidable on a pair of rods 51 fixed to lever 40. In the present instance the frame has pivoted thereto a pair of selectors 52 and 53, respectively. A rod 54 connects lever 34 with the slide 50 to 60 position the latter, depending upon which of the weaving shuttles is active, so that one or the other of the selectors will be in alignment with the setting finger 55. The latter forms part of a setting lever 56 operatively connected to the core 65 57 of a solenoid 58 mounted on the lever 40. The setting finger rocks in a plane fixed with respect to the lever 40.

The selectors are normally in the position occupied by selector 52 in Fig. 4, but at the time of 70 indication will rock to the position occupied by selector 53 in the same figure. The lower part of the selector is formed to direct the top of the latch against the lug 46, and the latch can engage but one at a time, namely, the one which is in 75 alignment with the finger 55. A stationary re-

setter 59 restores to normal the indicated selector which causes a shuttle change.

In the preferred form of the invention I employ a well-known weft detecting mechanism 65 of the so-called external type, having a body 66 mounted on a fixed support 67 preferably rigid with respect to the loom. A slide 68 in the body is movable toward and from the lay and has pivotally mounted at the rear end thereof a detector jaw 69. The latter has an indicating finger 10 70 extending forwardly of the pivot 71, and a spring 72 in the body holds the indicating finger against a stop pin 73 on the slide.

The lay has upper and lower shuttle boxes B¹ and B², respectively, which are normally down 15 so that the upper box is in picking position to receive each active shuttle when the latter is on the magazine side of the loom. As the lay advances the detector jaw will enter the shuttle box B¹ and the shuttle therein to detect condition of weft, 20 and if sufficient of the latter be present the detector jaw and slide will move forwardly. When insufficient weft is present, however, the slide remains at rest and the detector moves about the pivot 71 to cause the indicating finger 70 to engage an electric contact 74 mounted on an insulated support. When this happens current flows through the following circuit, see Fig. 1: ground G, wire 75, the solenoid 58, wire 76 to the source of electric power 77, wire 78 to the contact 74, finger 70 back to the ground, the frame of the feeler mechanism being grounded to establish an electric return. This results in attraction of the core 57 with a setting of one or the other of the 30 selectors, as previously described, depending upon which weaving shuttle is active. The detector mechanism may be the same as that shown in U. S. Patent to Payne No. 1,738,198, modified to 35 close an electric circuit.

The indication which is stored in the mechanism shown in Figs. 3 and 4 will effect a shuttle change on the second pick after indication if there is no shift of the boxes at the opposite end of the loom, and when this occurs the operating lever will rock to raise the boxes B¹ and B², and also 45 to actuate the magazine through one or the other of the pull rods 24 or 26.

The matter thus far described may be as set forth in the aforesaid applications and patents, and of itself forms no part of my present invention. 50

It is to be understood that in the loom to which my present invention applies the depleted shuttle is picked from the detector side of the loom when the lay is at top center and is boxed 55 a little more than one-half a pick later when the loom reaches protection point. Thereafter the shifting boxes will start to rise or fall if a change in active weaving shuttle is to occur, this shift continuing through front center and being completed when the lay is again at top center for picking. In order that the boxes at the magazine end of the loom may be shifted so that the depleted shuttle which is to arrive from the opposite or shifting shuttle box end of the loom 60 may enter the lower box B², the shift of these boxes starts shortly after the time for the drop boxes to begin their movement, with the result that the changing boxes will be shifting when the lay has moved them close to the weft detector. When the depleted shuttle reaches the magazine side of the loom it will enter the lower box B² which is temporarily raised on a line with the race, and the top box B¹ will receive a shuttle 65 from the magazine when the lay is in its rear- 70 75

ward position. When the lay again reaches the protection point in its forward motion the changing boxes can move down to bring the top box opposite the race for the following pick of the shuttle.

When the boxes start to rise in the operation just described, some provision must be made whereby their motion will not injure the detector jaw 69 and in carrying the preferred form 10 of my invention into effect I accomplish this result by a withdrawal of the detector prior to the rising of the boxes. In this form of the invention the cam 88 may be of the type set forth in the previously described applications to rock 15 the lever 42 as in previously known constructions. The feeler slide 68 has an upturned end 82 attached to a pull wire 83 which as shown in the present instance may pass through a coil wire sheath 84. The latter is fastened at its upper 20 end preferably to the stand of the feeler and at its lower end to the loom frame, the wire 83 extending beyond to have attachment with an extension 85 of the operating lever 40. This extension multiplies the motion of the lever so 25 that the detector is moved out at a faster rate than the boxes rise and I am therefore able to control both the rising of the boxes and the withdrawal of the feeler from the same moving part of the loom. I do not wish to be limited, 30 however, to this joint control of these parts.

The connection described not only holds the feeler out of the range of the moving empty boxes at the start of a changing operation, but also holds it out during return movement of the 35 boxes to normal position when both are occupied.

The detector passes through a slot 86 (Fig. 5) formed in a binder 87 which is stationary with respect to the lay, that is, the binder does not share the rising and falling movements of the 40 boxes B' and B². When the changing boxes reach normal down position the depleted shuttle in the lower box passes forwardly under the fixed binder.

The modified form of the invention employs 45 an electrical detector E comprising a body 99 of insulating material in which are located two detector wires 91 and 92, respectively. Each wire is surrounded by a coil spring 93 housed in a cavity in the body of the detector and located 50 between a shoulder 94 at the rear of the wire and a screw plug 95 threaded into the body of the detector and through which the wire is freely movable. Wires 96 and 97 are in electric contact with detector fingers or wires 91 and 92, 55 respectively. The bobbin 98 is provided with a ferrule or other metallic surface 99, which when uncovered will electrically connect the electrodes 91 and 92.

In order to support the detector I provide the magazine with a stand 100 and pivotally mount thereon as at 101 a supporting lever 102 the lower end of which has a platform 103 to which the detector is fastened by a bolt 104. Spring 105 is interposed between the lever and the stand 100 and acts to hold the detector yieldingly in rear position. A stop 106 on the stand 100 engages the lever to limit movement thereof under influence of the spring.

The electrodes enter the upper shuttle box, and the lay in the modified form, together with the shuttle boxes and magazine, may be as in the preferred form, except that the cover 107 of the box is modified. A leaf spring 110 secured 75 to the lever 102 has shoulders 111 and a tongue

112, the latter adapted to enter an opening 113 in the box cover 107.

In the operation of the modified form the cam 80 is altered so as to delay the time of rising of the changing boxes B¹ and B² until after 5 danger of engagement with the detector is passed. Closure of a circuit similar to that previously traced by the electrical connection of the electrodes 91 and 92 will result in upward movement of these changing boxes as the lay moves 10 rearwardly. When the box cover is lifted as in the preferred form a reserve shuttle will be drawn from the proper stack in the magazine to enter the upper box, and when the depleted shuttle is received by the lower box B² these 15 boxes will begin to move down as the lay moves forwardly. The box cover will be swung up as previously described when the lay is in rear position, but as the latter advances the cover 20 will return to assist in boxing the fresh shuttle 25 and will assume the position shown in Fig. 10. Further advance movement of the boxes will cause the tongue 112 to enter the opening 113 while the boxes are still somewhat above their normal downward position. The advancing box 30 cover thereafter engages the shoulders 111 to move the lever 102 forwardly from the position shown in Fig. 10 to that shown in Fig. 11 with the electrodes of the detector clear of the boxes and the shuttles contained therein. When the boxes are in low position the depleted shuttle 120 is ejected forwardly below the detector as shown in Fig. 11.

As the lay moves backwardly the tongue will 35 follow the cover until the lever 102 engages stop 106, after which the box cover will move away from the tongue and the spring will return to the normal position shown in Fig. 7. Thereafter forward movements of the lay will move the box 40 cover under the spring 110.

As shown in Fig. 9 the initial upward movement of the boxes preparatory to shuttle change will flex the spring 110 but the latter is able to yield without injury, and as previously described the cam will act to delay this upward movement until 45 after the boxes have moved rearwardly far enough to miss the fingers 91 and 92.

From the foregoing it will be seen that I have provided a weft detector of the external type on the magazine side of the shuttle changing loom 50 so constructed and arranged as to avoid injurious contact either with the shuttles or the boxes which are in motion relatively to the lay at the time of shuttle change. It will further be seen that the expelled shuttle is delivered from the 55 lay at a point below the detector, and that the loom operates with a binder on the magazine end of the lay stationary with respect to the latter so that the forward parts of the detecting mechanism are shielded by this binder against any 60 desire of the shuttle to move forwardly. It will further be seen that the parts are so related that a repeated indication cannot be given by the depleted shuttle to be expelled from the lay, and that the invention is equally applicable to detectors which derive their indication from a mechanical operation within a shuttle or electrically by engagement of a conducting surface.

Having thus described my invention it will be seen that changes and modifications may be made 70 therein by those skilled in the art without departing from the spirit and scope of the invention and I do not wish to be limited to the details herein disclosed, but what I claim is:

1. In a shuttle changing loom, a lay, a maga- 75

zine having a plurality of groups of reserve stacks of shuttles, means defining a common delivery throat for the magazine through which a shuttle drawn from any one of the groups passes at the 5 time of shuttle change, a shuttle box movable relatively to the lay and toward said throat at the time of shuttle change to receive a reserve shuttle, weft detecting mechanism to control the shuttle box and enter the latter to detect the 10 condition of weft therein, and means to prevent engagement of the detector and shuttle box when the latter moves toward the throat of the magazine.

2. In a shuttle changing loom having a lay, 15 a group of reserve shuttles, a shuttle box on the lay movable relatively to the lay toward the group to receive a reserve shuttle in a shuttle changing operation of the loom, a weft detector to enter the box on non-changing beats of the loom due 20 to movement of the box to detect the condition of weft therein and initiate a shuttle change at substantial exhaustion of weft, and means to withdraw the detecting mechanism from said shuttle when the latter moves toward the group.

25 3. In a shuttle changing loom having a lay, a group of reserve shuttles, a shuttle box on the lay, a detector to enter the box due to movement of the box to detect the condition of weft therein, means controlled by the detector to move the 30 shuttle box relatively to the lay toward the group in a direction transverse of the detector mechanism, and means to move the latter out of engaging relation with respect to the box when the latter moves toward the group.

35 4. In a shuttle changing loom having a lay, a group of reserve shuttles, a shuttle box on the lay normally spaced from the group, means to move said shuttle box toward the group to receive a reserve shuttle therefrom, weft detecting mechanism controlling said means and rendered effective by movement of the box to enter the shuttle box and detect the condition of weft therein when the box is in normal position, and means to move the weft detector to provide a 40 clear path for the shuttle box and reserve shuttle therein as said box and shuttle move from a position near the group to the normal position.

5. In a shuttle changing loom having a lay, a group of reserve shuttles, a shuttle box normally spaced from the group but movable with 50 respect to the lay toward the group, a weft detector mechanism to enter the shuttle box when the latter is in normal position to detect the condition of weft therein, and means to move the 55 shuttle box toward the group and also the detector out of the path of the shuttle box when the latter moves toward the group.

6. In a shuttle changing loom, a lay, a magazine having a group of reserve shuttles, a binder 60 on the lay stationary with respect thereto, a weft detector on the same side of the loom as the magazine to pass through the binder when detecting weft, a shuttle box movable between the binder and lay during a shuttle changing operation, and means to insure location of the weft 65 detector out of the range of movements of said shuttle box during a shuttle changing operation.

7. In a shuttle changing loom, a group of reserve shuttles, a weft detector adjacent the group, 70 a lay movable toward and from the weft detector, a pair of changing shuttle boxes on the lay under control of the detector, one of the boxes normally being positioned to receive the detector for normal detecting operations, and one of said boxes 75 to receive the depleted shuttle for forward eject-

ment therefrom, and means to relatively position the detector and the shuttle box which receives the depleted shuttle so that the detector will be vertically displaced from the path of the depleted shuttle as it is ejected from the shuttle 5 box in which it has been received.

8. In a shuttle changing loom, a group of reserve shuttles, a weft detector adjacent the group, a lay movable toward and from the detector, a pair of shuttle changing boxes on the 10 lay normally in down position so that the upper box is operatively placed with respect to the detector for the normal detecting operation, means controlled by the detector to raise the boxes and to effect movement of a reserve shuttle 15 from the group to the upper box and receipt of the depleted shuttle in the lower box, and means to thereafter lower the boxes for the ejection of the depleted shuttle from a position below the weft detector.

20 9. In a shuttle changing loom, a group of reserve shuttles, a weft detector adjacent the group, a lay movable toward and from the detector, a pair of shuttle changing boxes on the lay, a binder substantially stationary with respect to 25 the lay, said binder normally being above the lower box when said boxes are in normal position, and the detector normally passing through the stationary binder to enter the upper box to detect the condition of weft therein, and means 30 controlled by the detector to raise the boxes so that the lower box receives the depleted shuttle, said means thereafter lowering the boxes so that the depleted shuttle is ejected forwardly 35 below the binder and the detector.

10. In a shuttle changing loom operating with a plurality of weaving shuttles any one of which may become active, a magazine having a plurality of groups of reserve shuttles, one group for each active shuttle, a shuttle box to receive 40 any weaving shuttle that is active, a weft detecting mechanism to enter the shuttle box and detect condition of weft therein, a lay to move the box toward and from the weft detector means under control of the weft detector to move the 45 box toward the magazine to receive a shuttle from the group corresponding to the active shuttle, and means to insure non-interference on the part of the detector with the movement of the shuttle box toward the magazine.

50 11. In a shuttle changing loom, a plurality of groups of distinctive reserve shuttles, a weft detector on the reserve shuttle side of the loom to detect the condition of weft in an active shuttle, a lay movable toward and from the detector selector mechanism operatively interposed between the detector and groups, the weft detector to detect when the lay is forward and means jointly controlled by the detector and selector to replace a depleted active shuttle with a reserve 60 shuttle of the same kind while the lay is in rearward position.

12. In a shuttle changing loom, a magazine of reserve shuttles, a lay movable back and forth, a weft detector on the magazine side of the loom 65 to enter the active shuttle when the lay is in forward position and detect weft therein, and means controlled by the detector to replace a depleted active shuttle with one from the magazine when the lay is in rear position, the lay discharging 70 the depleted shuttle when said lay is in forward position.

13. In a shuttle changing loom, a reserve shuttle magazine at one end of the loom, a lay movable back and forth under the magazine, a 75

weft detector on the magazine side of the loom mounted in front of the lay to have a detecting action with respect to the active shuttle due to movement of the lay, a slide on which the detector is mounted, and means to move the slide forwardly on changing beats of the loom to move the detector to a position of non-interference with the shuttle changing operation.

14. In a shuttle changing loom, a magazine for 10 reserve shuttles, a lay, a shuttle box on the lay under the magazine to receive the active shuttle and also to receive a reserve shuttle from the magazine, a side slipping weft detector to enter the box to detect the condition of weft in the 15 active shuttle, and means to withdraw the side slipping detector from the shuttle box on shuttle changing beats of the loom.

15. In a shuttle changing loom, a group of 20 reserve shuttles at one end of the loom, a lay movable back and forth under the group, a shuttle box on the lay to receive the active shuttle and movable toward the group to receive a reserve shuttle, a pair of electrical weft detectors insulated from each other caused to enter the 25 shuttle box due to movement of the latter toward the detector to determine the condition of weft in the box and initiate movement of the shuttle box toward the group, and means under control of the detector to move the latter out of the path 30 of the shuttle box as the latter moves during the shuttle changing operation of the loom, thereby preventing contact of the detectors with the shuttle box to prevent a repeated indication by the detector.

35 16. In a shuttle changing loom, a magazine for reserve shuttles, a lay movable back and forth under the magazine, a shuttle box carried by the lay under the magazine, a weft detector to enter the shuttle box to determine the condition of weft therein and initiate movement of a reserve 40 shuttle toward the shuttle box upon depletion of weft in the active shuttle, a support for the detector movably mounted on and with respect to the magazine, and means to move said support together with the detector forwardly from the 45 lay to prevent the detector from interfering with the shuttle changing operation of the shuttle box.

17. In a shuttle changing loom, a lay movable 50 back and forth, a reserve shuttle magazine located near the backward limit of movement of the lay, a weft detector mounted in front of the lay near the forward limit of movement of the lay and effective to control the magazine, and a 55 shuttle box on the lay to be entered by the weft detector when the lay is forward and to receive a shuttle from the magazine when the lay is rearward.

18. In a shuttle changing loom, a lay movable 60 back and forth between front and rear extreme positions, a magazine of reserve shuttles near one extreme position, a weft detector to control the magazine near the other extreme of motion of the lay, and a shuttle box movable with the lay 65 between the magazine and the detector, said box to coact with the detector on a forward stroke of the lay and to coact with the magazine on a subsequent backward stroke of the lay.

19. In a shuttle changing loom operating with 70 a lay having upper and lower shuttle boxes at one end of said lay, a group of reserve shuttles at the same end of the lay, a weft detector at the same end of the lay normally maintained at a given level to detect the condition of weft 75 in the active shuttle, and means carried in part

by the lay and dependent upon indication of weft exhaustion in the depleted active shuttle by the detector to effect reception of a reserve shuttle from the group in the upper shuttle box at a level above the level of the detector, to effect 5 reception of the depleted active shuttle on the shuttle changing beat of the loom in the lower shuttle box and at the level of the detector, and to subsequently eject the depleted shuttle from said lower box at a level below that of the detector and in a direction toward said detector.

20. In a shuttle changing loom having a lay 10 having a plurality of shuttle boxes, a group of reserve shuttles, a weft detector mounted in front of the lay and having a detecting relation 15 with respect to the active shuttle because of forward motion of the lay, said detector operating at a given level, and means carried in part by the lay and moving back and forth with the latter and controlled by the detector when the 20 latter indicates exhaustion of weft in the active shuttle to render said means effective to receive a reserve shuttle from the group in a box above said level and to receive the depleted active shuttle in a second box substantially at said level, 25 said means subsequently operated to move the reserve shuttle substantially to said level and to move the depleted shuttle and its box below said level, the lay being effective on a forward beat thereof to eject the depleted shuttle from said 30 box at a level below that of the detector and in a direction toward said detector.

21. In a shuttle changing loom, a lay movable 35 back and forth therein, a reserve shuttle magazine, a shuttle box on the lay, a weft detector mounted in front of the lay near the forward limit of movement of the lay and positioned to enter the shuttle box as the lay moves forwardly, and mechanism controlled by the weft detector to effect transfer of a reserve shuttle from 40 the magazine to the shuttle box when the lay is substantially at the limit of its rearward movement.

22. In a shuttle changing loom having a lay, 45 a group of reserve shuttles, shuttle boxes normally stationary with respect to the lay but shiftable relatively thereto to receive a shuttle from the group on shuttle changing beats of the loom when the lay is in rearward position, a weft detector rendered operative by lay motion normally to enter one of the shuttle boxes when the 50 lay is in forward position with the boxes stationary relatively to the lay, and means to withdraw the detector from the path along which the shuttle boxes shift during a shuttle changing 55 operation of the loom.

23. In a shuttle changing loom, a lay having 60 a shuttle box, a weft detector mounted in front of the lay on the same side of the loom as said shuttle box and toward and from which the 65 shuttle moves with the lay, means to effect an additional relative movement between said box and said detector, and means controlled by the detector to effect discharge of a depleted shuttle directly forwardly from said shuttle box on the 70 detector side of the loom and along a path below said detector.

24. In a shuttle changing loom, a lay having 75 a shuttle box, a group of reserve shuttles at one side of the loom, a weft detector mounted at the same side of the loom at a given level to have detecting relation with the active shuttle, means controlled by the detector to effect reception of a depleted shuttle in said box at the level of the detector, means to effect relative vertical move- 80

ment between said box and said detector, and means subsequently to effect discharge of the depleted shuttle directly forwardly from said box at a level lower than that of the detector.

5 25. In a shuttle changing loom, a lay, shuttle box mechanism movable relatively to the lay, a weft detector mounted in front of the lay at a given level to detect the active shuttle due to forward motion of the lay, control connections 10 between the detector and the shuttle box mechanism to render the latter effective to receive a depleted shuttle at the level of the weft detector, means to effect relative vertical movement between said box and said detector, and 15 means to subsequently effect discharge of the depleted shuttle from the shuttle box mechanism directly forwardly toward the detector at a level lower than that of the weft detector.

26. In a shuttle changing loom, a magazine for reserve shuttles, a lay movable back and forth under the magazine, a shuttle box, carried by the lay under the magazine and having an active cell and an auxiliary cell, means to shift said box vertically during shuttle replenishment, a weft detector to enter the shuttle box to determine the condition of weft therein and initiate movement of a reserve shuttle toward the shuttle box upon depletion of weft in the active shuttle, a 10 movably mounted support for the detector, and means to move said support together with the detector forwardly from the lay to prevent the detector from interfering with the vertical movement of the box during the shuttle changing operation. 15
